Primary Examiner — T Chase Nelson*Assistant Examiner* — Jonathan J. Han*(74) Attorney, Agent, or Firm* — RatnerPrestia(57) **CLAIM**

The ornamental design for a spoiler for motor vehicle, as shown and described.

DESCRIPTION

FIG. 1 is a rear side perspective view of a spoiler for motor vehicle;

FIG. 2 is a front side perspective view thereof;

FIG. 3 is a front elevation view thereof;

FIG. 4 is an elevation view thereof from the right side, the left side being a mirror image thereof;

FIG. 5 is a rear elevation view thereof;

FIG. 6 is a top plan view thereof; and,

FIG. 7 is a bottom plan view thereof.

The broken lines are used for the purpose of illustrating portions of the spoiler for motor vehicle that form no part of the claimed design.

1 Claim, 4 Drawing Sheets(56)
